RADIO TUNING MECHANISM

Stanley S. Cramer, Haddon Heights, N. J., assignor to Radio Condenser Company, Camden, N. J.

Application May 9, 1940, Serial No. 334,151

23 Claims. (Cl. 74—10)

This invention relates to a special combination and unitary structure for use in connection with radio receiving sets.

Numerous radio receiving sets are being made today in which push-button tuners are used, wherein the push-button structure for operating the tuning condenser is made as a separate unit from the condenser or tuning elements per se, some form of indirect drive being used to couple the push-button unit with the condenser tuning unit.

Instead of having two independent units with the interconnecting coupling means, my present invention is directed to a single unitary structure in which the tuning condenser or condensers and the push-button parts are incorporated with or carried by the same frame members. By combining the various parts into a unitary structure, I reduce the size and cost of the radio tuning equipment, thereby fulfilling one of the principal objects of my invention.

Another object of my invention is to provide a construction in which the tuning elements, such as the stator and rotor of a variable condenser, are so arranged that the full range or capacity of the condenser may be covered by a direct-acting push-button unit, without any intermediate gearing.

An important object of my invention is to provide new and novel means for taking out back-lash and wobble in the tuning units.

A further object of my invention is to provide new and novel means for adjusting and locking the setting device which controls the movement of the rotor shaft without throwing the tuning element off the set resonance point.

Other and more specific objects will be apparent to one skilled in the construction of such equipment to which this invention relates.

In the drawing:

Figure 1 is a plan view of a two-gang condenser incorporated in the unitary structure, along with four push-button tuning elements, similar parts being omitted to accommodate the views on the drawing.

Figure 2 is a view on the line 2—2 of Figure 1.

Figure 3 is a view on the line 3—3 of Figure 1.

Figure 4 is a perspective view of the setting member and its parts in disassembled position.

Figure 5 is a fragmentary view across two of the push-button elements just in front of the forward part of the frame member.

Figure 6 is an enlarged view on the line 6—6 of Figure 5.

Figure 7 is a fragmentary, perspective view of the parts shown on the line 7—7 of Figure 6.

In the various views, wherein like numbers refer to corresponding parts, 1 is a front frame member having lugs 2 and 3 bent backwardly, which are attached in any suitable manner as by screws 4 to the end plates 5 and 6 which are fastened together by studs 7 and 8 in a manner such as disclosed in my Patent No. 2,101,985, issued December 14, 1937.

As an alternative, the frame member 1 may be omitted and the end plates 5 and 6 bent outwardly to form what are now the extending ends 9 and 10 of the frame member 1. By constructing the end plates 5 and 6 in this last-mentioned manner, the front portions of the stators 11 and 12 are left exposed. I prefer to mount the stators 11 and 12 to the frame bars or rods 7 and 8 in the manner disclosed in my Patent No. 2,187,017, issued January 16, 1940. Further description of the frame and mounting of the stator therein is therefore not necessary.

The rotor plates of the condensers are mounted directly on the rotor shaft 13 which, in turn, is supported in the end plates 5 and 6 in the manner disclosed in my Patent No. 1,800,719, issued April 14, 1931. The rotor shaft 13 extends through the end plates 5 and 6 to receive setting devices, two forms of which and two methods of mounting are shown in Figure 1.

In the preferred form, shown in the two push-button structures at the left of Figure 1, the setting device 14 comprises a punching of suitable sheet metal such as steel, comprising a flat portion with two arcuately formed edges 15 and 16 and a circular or ring portion 17 held to the plate portion 14 by an integral yoke 18. The plate portion 14 and ring 17 have holes 19 and 20 respectively therein which are adapted to make a snug fit with the rotor shaft 13. Positioned between the plate 14 and ring 17 is a bushing 21 having a screw-threaded hole 22 to receive a set screw 23 which is adapted to pass through a hole 24 in the yoke 18 and into the bushing 21 and against the shaft 13, thereby drawing the bushing against the shaft to form a double lock between the bushing, shaft and screw.

The yoke 18 is provided with a pair of oppositely disposed fingers 25 which are adapted to hold a resilient metal member 26 in position between the yoke 18 and the shaft 13 when it is found desirable to use such a resilient member. The member 26 has slots 28 to receive the fingers 25 to hold the member 26 in place when it is used. The bushing 21, in this case, is provided

with a flat surface 27 to form a seat for the member 26.

The arcuate surface 16 of the flat plate portion of the setting device 14 terminates in a straight edge 29, while the edge 15 terminates in a curved recess 30. The portions 29 and 30 are adapted to be engaged by fingers or projections 31 and 32 which are preferably offset or punched outwardly from the slidable plate member 33. Which has a slot 34 therein through which the shaft 13 passes. The projection 32 in its engagement with the notch 38 only engages the top inner edge thereof. This will force the inner end of the slidable member 33 downwardly so that the upper edge 54 of the slot 34 is drawn downwardly against the shaft 13.

One end of the sliding member 33 has a two-step end reduction, one step, 35, being adapted to project through and fit in slots in the frame portion 9. The other step portion, 36, is wider than the portion 35 so as to provide shoulders for stopping the plate 33 against the frame member 8, due to the action of the retracting spring 37 after the finger has been released from a button 38 carried by a rod 39 which, in turn, is supported by front and rear lugs 40 and 41, respectively, punched outwardly from the slidable plate member 33. It will be noted that the return spring 37 in Figure 2 acts at an angle to assist in holding the slidable member 33 downwardly against the shaft 13, so that when the pressure is released from the push-button, the spring 37 will act in a direction to prevent the projection 32 from moving the setting device.

Immediately adjacent the lug 40, the rod 39 is provided with a collar 42 against which one end of a spring 43 is seated, the other end of the spring being seated against the lug 41. The spring 43 is stiff enough so that for normal operation or tuning in of the stations, by any one of the push-buttons, it is compressed just a little or not at all by the pressure required to turn the rotor of the condenser. The collar 42 may be made integral with the rod 39, or the rod 39 may have an annular groove therein to receive a snap ring which would then form the collar 42. The inner end of the rod is flattened at 44 to form an end similar to a screw-driver to engage the slot in the screw 23 for a purpose which will be later pointed out.

The outer end of the push-rod 39 is preferably also flattened to fit a slot cast in the button 38 which in turn may have a screw-driver slot 45 for a purpose which will be hereinafter pointed out.

In the form of setting member shown to the right of Figure 1, the setting member is spaced from the end plate 6 by a collar 46, and the yoke portion 18 itself is threaded, and the screw 23 pushes directly against the spring member 26, which may be bowed to fit the periphery of the shaft 13 as shown in Figure 3. In this figure, the setting member 14 has two flat engaging surfaces 29 similar to the one known in Figure 2.

By utilizing the form of construction shown at the left of Figure 1, as heretofore described, instead of the arrangement shown to the right of Figure 1, it will be noted that the entire structure may be shortened materially.

In the operation of the structure, and referring to Figures 1 and 2, when it is desired to set a station on a given frequency the button 38 is pushed in so that the screwdriver end 44 will engage the slot in the screw 23, it being understood that the push-rod 39 is rotatable

within its mounting lugs 40 and 41. Sufficient pressure is put against the button 38, either by the fingers engaging the knurled portion of the button or by a screw-driver in the slot 45, to cause this engagement of the screw-driver end 44 with the screw slot against the compression of the spring 43. The set screw is loosened and the station is tuned in by a manual control means which is not shown, and the screw 23 is tightened up to lock the setting member 14 in its tuned position, it being understood that the slidable member 33 is in a position so that the projections or fingers 31 and 32 engage their respective seats 29 and 30 on the setting member 14. After this station has been set to its tuned position, all that is required to bring in this station the next time, is merely to push in its corresponding button 38.

To overcome any up-and-down lost motion in the outer end 35 of the sliding member 33, a bar 47 is fastened to the frame portions 9 and 10 by means of screws 48, there being a separate plate 47 for each pair of push-buttons.

An alternative construction is shown in Figures 5 and 6, in which a thin, resilient plate member 49, preferably of spring steel, is used instead of the bars 47. In this construction the plate 49, which need only be fastened at one end to the member 9 as by screws or rivets 50 is slotted at 51 to accommodate the end 35 of the sliding push-button plates, the outer end of each having a hole therein to receive a ball-type member 51 which is anchored to the end 35 in any satisfactory manner as by a press-fit, soldering or spot-welding at 52. On pushing in the plate 35, the ball member 51 is adapted to slightly enter a hole 53 in the spring member 49 and move this member, which is preferably slightly bowed at the center, toward the frame member 9. The fit of the ball 51 in the spring member 49 will then eliminate all wobble in this end of the push-button plate 35. Furthermore, since the member 49 is slotted, it can spring somewhat sideways to accommodate the partial entry of the ball 51, without severe binding, but sufficiently to prevent up-and-down or side-wobble, thus inuring to the more accurate setting of the setting device.

While I have shown the push-button tuners 60 on both sides of the tuning condenser, they may of course be placed together on one side. Furthermore, the construction of the tuning mechanism per se may be mounted in a frame separate from the condenser frame as an independent tuner, which may be connected to the rotor shaft of the condenser in any satisfactory manner.

From what has been said, it will be appreciated that many of the details for carrying my improved construction into operative effect may be varied without departing from the spirit of the invention or the scope of the appended claims.

What I claim is:

1. A unitary structure for the purpose described including a frame and at least one stator and rotor having a shaft carried by the frame; a plurality of slidable members carried by the frame with means for actuating said members to tuning position, each slidable member having a slot through which the rotor shaft passes, and projections located one on opposite sides of said slot but on the same side of the slidable member which also has lugs on this same side for carrying said actuating means, and a set-

ting device adjustably carried on and fastened to the rotor shaft and having surfaces and stop parts disposed on opposite sides of the rotor shaft and engaged by said projections to turn the setting device and rotor shaft in a direction according to the predetermined adjustment of the setting device.

2. A structure as set forth in claim 1, further defined in that the setting device includes a flat portion carrying said projection-engaging-surfaces, and a ring portion connected by a yoke, the rotor shaft passing through both the flat portion and the ring, a screw going through the yoke and acting to fasten the setting device in position on the rotor shaft.

3. A structure as set forth in claim 1, further defined in that the setting device includes a flat portion carrying said projection-engaging-surfaces, and a ring portion connected by a yoke, the rotor shaft passing through both the flat portion and the ring, the yoke having oppositely disposed fingers, a resilient metallic member located between the yoke and rotor shaft and having slots for receiving said yoke finger, and a screw going through the yoke and acting to fasten the setting device in position on the rotor shaft.

4. A structure as set forth in claim 1, further defined in that the setting device includes a flat portion carrying said projection-engaging-surfaces, and a ring portion connected by a yoke, the rotor shaft passing through both the flat portion and the ring, the yoke having oppositely disposed fingers, a resilient metallic member located between the yoke and rotor shaft and having slots for receiving said yoke finger, the resilient member having its central portion curved to arcuately engage the rotor shaft over a considerable area, and a screw going through the yoke and forcing the curved part of the resilient member into clamping engagement with the rotor shaft.

5. A structure as set forth in claim 1, further defined in that the setting device includes a flat portion carrying said projection-engaging-surfaces, and a ring portion connected by a yoke, a bushing positioned between the ring and flat portions, the rotor shaft passing through both the flat and ring portions as well as the bushing, and a screw going through the yoke and into the bushing to clamp the setting device securely to the rotor shaft.

6. A structure as set forth in claim 1, further defined in that the setting device includes a flat portion carrying said projection-engaging-surfaces, and a ring portion connected by a yoke, a bushing positioned between the ring and flat portions, the rotor shaft passing through both the flat and ring portions as well as the bushing, the yoke having oppositely disposed fingers extending over opposite portions of the bushing, and a screw going through the yoke into the bushing to draw the two toward each other and securely clamp the setting device to the rotor shaft.

7. A structure as set forth in claim 1, further defined in that the setting device includes a flat portion carrying said projection-engaging-surfaces, and a ring portion connected by a yoke, a bushing positioned between the ring and flat portions, the rotor shaft passing through both the flat and ring portions as well as the bushing, the yoke having oppositely disposed fingers extending over opposite portions of the bushing, a resilient metallic member located between the yoke and the bushing and having slots through

which said fingers pass, and a screw going through the yoke and resilient member into the bushing for clamping the setting device to the rotor shaft.

5 8. A structure as set forth in claim 1, further defined in that the surfaces on the setting device which are engaged by said projections are arcuately formed parts on the edge of a flat portion of the setting device, while the stop parts 10 are straight edges which form right angles to the axis of the slidable member when the parts are in tuning position.

9. A structure as set forth in claim 1, further defined in that the surfaces on the setting device which are engaged by said projections are arcuately formed parts on the edge of a flat portion of the setting device, while at least one stop part is a straight edge which forms substantially a right angle with the axis of the slidable member when the parts are in tuning position, the other stop part being a notch into which its cooperating projection on the slidable member extends in the manner described at the tuning position.

25 10. A structure as set forth in claim 1, further defined in that the actuating means comprises a push-rod slidably carried by said lugs, the rod having a fixed collar positioned against the outer lug when the slidable member is in normal idle position, and a spring between the collar and the inner lug of sufficient strength to allow the slidable member to be moved to tuning position with little or no further compression of the spring beyond its normal tension.

30 11. A structure as set forth in claim 1, further defined in that the actuating means includes a push-rod rotatably and slidably carried by said lugs, the rod having a fixed collar spaced from the rear lug and a relatively stiff spiral spring positioned between the collar and the rear lug, the spring being stiff enough to permit full movement of the slidable member to tuning position without being compressed any substantial amount, the inner end of the push-rod terminating in a screw-driver point that is in alignment with the fastening means on the setting device which in turn is adapted to be engaged by the screw-driver point of the rod on extra pressure being applied thereto, whereby the fastening may be operated to adjust the setting device.

40 12. A unitary structure for the purpose described including a frame and at least one stator and rotor having a shaft carried by the frame and extending through the frame on opposite sides thereof; a plurality of slidable members carried by each side of the frame at right angles to said shaft extensions, each slidable member having a slot therein through which the related rotor shaft end passes, projections on each slid- 45 able member, located one on each side of the slot but in vertical alignment on the same side of the slidable member, longitudinally spaced lugs on each slidable member and a push-rod carried by said lugs, and a setting device for each slidable member adjustably carried on the rotor shaft and having a part with surfaces adapted to be engaged by said projections to turn the setting device and rotor shaft to a fixed position as determined by the adjustment of the setting device.

60 13. A unitary structure for the purpose described including a frame and at least one stator and rotor having a shaft carried by the frame and extending through the frame on opposite sides thereof; a plurality of slidable members carried by each side of the frame at right angles

to said shaft extensions, each slidable member having a slot therein through which the related rotor shaft end passes, projections on each slid-able member, located one on each side of the slot but in vertical alignment on the same side of the slidable member, longitudinally spaced lugs on each slidable member and a push-rod carried by said lugs, the rod being rotatable in said lugs and having a collar spaced from the rear lug and a relatively stiff spring carried by the rod be-tween the collar and the rear lug, and a setting device for each slidable member carried on the shaft and having fastening means for anchoring it thereto, the rod being longitudinally movable against the compression of said spring after the slidable member has been moved to tuning position, to engage the fastening means to operate the same for adjusting the arcuate position of the setting device on the rotor shaft.

14. A structure as set forth in claim 1, further characterized in that the slidable members are flat metal strips set on edge in the frame, and metal bars are fastened to a frame member across and in engagement with the edges of the slidable member in pairs for the purpose described.

15. A structure as set forth in claim 1, further characterized in that the slidable members are flat metal strips set on edge in the frame, ball-like pieces set in the outer ends of said slidable members and thin flat spring strips fastened to the outer surfaces of a front frame member, the strips having holes therein slightly smaller than said ball pieces, the strips being slotted for a distance from said holes to receive the slidable member and to also allow cooperative action between the spring and ball piece for the purpose described.

16. In a tuning structure for a radio-receiving set including a frame and a stator and rotor carried by the frame, the rotor having a shaft extending through a frame member, a setting device carried on the shaft extension and having fastening means for securing it to the shaft, a slidable metal plate set on edge and supported at one end by the rotor shaft and at its opposite end by a frame member, a push-rod rotatably and longitudinally movably carried on the slid-able plate, the push-rod having its inner end formed to engage said fastening device to operate it so the setting device may be adjusted to a desired setting, means on the slidable plate for engaging the setting device to turn it and the rotor shaft in the desired direction, and means on the push-rod for allowing it to be moved lon-gitudinally beyond its position for normal tun-ing in order to make the engagement with the fastening means as described.

17. A tuning structure as set forth in claim 16, further defined in that the setting device comprises a metallic member having a ring portion and a plate portion extending across the shaft and joined by a yoke to the ring, the motor shaft going through both the plate and ring, the plate portion having cam edges at opposite ends, the cam edges terminating in stop portions, the engaging means on the slideable plate being projections offset therefrom, while the fastening means on the setting device includes a bushing on the rotor shaft located between said ring and yoke-connected plate with a screw going through the yoke and into the bushing.

18. A tuning structure as set forth in claim 16, further defined in that the setting device comprises a metallic member having a ring portion

and a plate portion extending across the shaft and joined by a yoke to the ring, the rotor shaft going through both the plate and ring, the plate portion having cam edges at opposite ends, the 5 cam edges terminating in stop portions, the engaging means on the slidable plate being projections offset therefrom, while the fastening means on the setting device includes a bushing on the rotor shaft located between said ring and yoke- 0 connected plate, and a resilient metal strip between the yoke and bushing, with means for holding the said strip in position and a screw going through the yoke, the strip and into the bushing to the shaft, and means on an outer 5 member of the frame for preventing wobble in the outer end of the slidable plate.

19. Tuning means for a radio-receiving set including a frame, a shaft carried by the frame and operatively connected with a tuning element, a setting device carried on the shaft and having fastening means for securing it to the shaft, a slidable member having one end supported by the shaft and the other end by a frame member, a push-rod rotatably mounted on one side of the slidable member and also being mounted for longitudinal movement, independent of movement of the slidable member, the end of the rod being formed to engage said fastening means on the setting device when it is given said independent movement, so as to act on the fastening means for releasing and fastening the setting device in an adjusted position on said shaft, and means on the slidable member for moving the setting device to turn the shaft in either direction of rotation according to the position of the setting device.

20. Tuning means for a radio-receiving set including a frame, a shaft carried by the frame and operatively connected with a tuning element, a setting device carried on the shaft and having fastening means for securing it to the shaft, a slidable member having one end supported by the shaft and the other end by a frame member, means for operating the slidable member, means on the sliding member for moving the setting device to turn the shaft in either direction of rotation according to the position of the setting device, and means for automatically taking up all play in the parts as a station is tuned in.

0   21. Tuning means for a radio-receiving set including a frame, a shaft carried by the frame and operatively connected with a tuning element, a setting device carried on the shaft and having fastening means for securing it to the shaft, a slideable member having one end supported by the shaft and the other end by a frame member, means for operating the slideable member, means on the sliding member for moving the setting device to turn the shaft in either direction of rotation according to the position of the setting device and means cooperative between the shaft, the setting device and the slideable member for removing all lost motion and play at the setting device when tuning in a station.

22. Tuning means for a radio-receiving set including a frame, a shaft carried by the frame and operatively connected with a tuning element, a setting device carried on the shaft and having fastening means for securing it to the shaft, a slideable member having one end supported by the shaft and the other end by a frame member, means for operating the slideable member, means on the sliding member for moving the setting

device to turn the shaft in either direction of rotation according to the position of the setting device, and means carried by the frame at the front thereof cooperative with means at the front end of the slidable member for eliminating all wobble of the slidable member when it is moved to final tuning position.

23. Tuning means for a radio-receiving set including a frame, a shaft carried by the frame and operatively connected with a tuning element, a setting device carried on the shaft and having fastening means for securing it to the shaft, a slidable member having one end sup-

ported by the shaft and the other end by a frame member, means for operating the slidable member, means on the sliding member for moving the setting device to turn the shaft in either direction of rotation according to the position of the setting device, and means for automatically and simultaneously taking up all play and wobble at the setting device and at the forward part of the slidable member when the 10 slidable member is moved to full tuning position.

STANLEY S. CRAMER.
